UNITED STATES PATENT OFFICE.

SAMUEL A. BLISS, DECEASED, LATE OF PEORIA, ILLINOIS, BY ANNIE L. BLISS,
ADMINISTRATRIX.

BURNER FOR PROJECTION-LANTERNS.

1,367,582.

Specification of Letters Patent.

Patented Feb. 8, 1921.

Application filed November 14, 1918. Serial No. 262,560.

To all whom it may concern:

Be it known that SAMUEL A. BLISS, formerly a citizen of the United States, and residing at Peoria, in the county of Peoria and 5 State of Illinois, now deceased, did invent certain new and useful Improvements in Burners for Projection-Lanterns; and ANNIE L. BLISS, administratrix of the estate of said SAMUEL A. BLISS, deceased, does hereby 10 declare that the following is a full, clear, and exact description of the invention, which will enable others skilled in the art to which it appertains to make and use the same.

This invention relates to a burner adapted 15 for the use of two dissimilar gases burned simultaneously as employed in projection lantern work.

The object of the invention is the provision 20 of a structure in a burner of the class named by which a necessary thorough mixture of the gases, oxygen and acetylene, can be used without so called "back-firing" and "popping" peculiar to such gases in lantern and other work.

25 The disadvantage in most burners for the above purpose, especially when combining such gases as oxygen and acetylene gases, is that thorough mixing of these gases does not properly take place which, together with the 30 fact that the structures do not prevent back-firing and popping, the light produced is unsteady and for that reason very unsatisfactory for projection purposes and particularly in motion picture work.

35 The device of this application has been designed to bring about the thorough mixture of the gases and to wholly prevent the disadvantages named.

To the end that the invention may be understood the accompanying drawing is provided, showing the preferred structures for accomplishing the purpose intended, though it is to be understood that changes may be made that may be considered the equivalent 45 of the structures shown and that will fairly fall within the scope of the appended claim.

Figure 1 is a side elevation of the burner;

Fig. 2 is a longitudinal section of certain of the parts, shown in Fig. 1 on line 2—2;

50 Fig. 3 is also a longitudinal section of portions of the same and certain other parts taken on said line; and,

Fig. 4 shows a slight modification of what is illustrated in Fig. 2.

55 The body of the device first to be described

is not unlike the devices now in common use wherein 1 and 2 indicate two tubes each for carrying a different gas, said tubes being carried in the customary manner in brackets 3 and 4. 5 is a supporting bracket carrying the structure supported upon any usual standard 6 upon which it may be vertically adjusted, and secured in position by a setscrew 7. The tubes extend through said bracket 5 and the latter has a screw 8 by 60 which the tubes may be secured in any desired longitudinal adjustment.

9 is a receptacle for the usual lime cylinder 10, being supported upon a thread-bar 11 extending through an ear 12 of the described 70 bracket 4. 13 is a pinion through which the thread-bar is slidable. It has a screw 14 whose point engages in a keyway 15 in said thread-bar, 16 being a wing-nut to lock the thread-bar when desired.

75 17 is a pinion mounted on the usual rod 18 by which the lime may be adjusted vertically. At one end each of the tubes is connected with the container (not shown) which supplies the gases through flexible tubes 19 and 80 20. Their other ends communicate through passages 21 and 22, Fig. 2, with the recess 23 of a member 24, see Fig. 2. As thus far described the device does not differ materially from those now in common use but the 85 novel features forming the subject of the invention will now be set forth.

25 is a tube inserted in the recess 23 of said member 24, one of whose extremities terminates in the bottom of said bore, at its other 90 end closing the open end of the recess in a gas-tight manner and preferably having a threaded boss 26. 27 is a nipple having threaded engagement with the said boss 26 and provided with a passage 28. 29 is a 95 second nipple having threaded engagement with the first. This said nipple 29 forms the burner from which the gases are projected upon the lime cylinder 10 through a jet orifice 30.

100 It is observed that the nipple 27 has a recess 31 which lies between the bore of the tube 25 and the reduced passage 28. It is further observed that the nipple 29 has the recess 32. The burner thus constructed is 105 particularly adapted for use with oxygen and acetylene, as already stated, usually furnished in separate tanks under pressure, these gases requiring a structure in a burner by means of which they will be very thor- 110

oughly mixed before being permitted to issue at the jet orifice 30.

This mixing may be initially done in several ways, two of which I have illustrated 5 in the drawing.

In Fig. 2 it is observed that the passages 21 and 22 are somewhat removed from the bottom of the recess 24, and that the tube 25 lies close to the bottom of the latter beyond 10 said passages whereby an intermingling or mixture of the two gases is initially accomplished before they enter the said tube 25.

In Fig. 4 the tubes indicated at 1 and 2 in Fig. 1 are in this case denoted by the numerals 33 and 34, the last named one having 15 a terminal end terminating near the upper portion of the member 24 and made to communicate with the recess 23 through a passage 35. By this means both gases are introduced at points more distant from the 20 entrance to the tube 25 than in the first instance and mixed before entering said tube 25. After mixture in either of these ways the said mixture reaches, under considerable 25 pressure, the recess 31 of the nipple 27 from which it passes into and through the passage 28 of greatly reduced diameter thence in the recess 32 of the nipple 29 and finally issuing through the jet orifice 30.

30 The gases moving out of the bore of the tube 25 enter the smaller passage or bore 28 and, in addition, are compelled to pass through the relatively larger recess 31 by which method they are thoroughly intermingled before reaching the jet orifice. Again, by being caused to increase in velocity by their passage from the nipple 27 into the large recess 32 of the nipple 29 they must again be mixed before issuing through 40 the jet orifice.

The bore 28 may be slightly greater in diameter than the bore of the jet orifice but much smaller than the bore of the tube 25 and thereby the flow of gases is changed 45 in velocity and made to attain the best pos-

sible form for use. The burner as constructed will use pressures as low as one and one half pounds and as high as desired without back-firing or popping, the peculiar arrangement described providing against the 50 latter.

It is not the wish to be confined to the use of the two nipples necessarily, but rather to provide any structure wherein the described relation of recesses and passages is 55 present to obtain the results named.

Having thus described the invention, what is claimed is—

In a device of the class described, the combination of a member provided with a bore of uniform diameter throughout closed at one end, and a second member closing the opposite end of said bore having an extension of substantially uniform diameter throughout depending into the said bore 60 terminating in spaced relation to the first described member at the bottom, and spaced from the side walls of the bore creating a substantially uniform annular space of considerable depth between the two members, 70 there being a pair of passages through the walls of the first member communicating with the said annular space opening directly into the same remote from the bottom of the said bore, there being also a passage extending longitudinally through the second described member communicating with the bottom of the bore of said first member, and a burner tube terminating the opposite end of the said second member communicating with 80 said bore.

In testimony whereof I affix my signature in presence of two witnesses.

ANNIE L. BLISS,
Administratrix of the estate of Samuel A.
Bliss, deceased.
